UNITED STATES PATENT OFFICE.

JOHN T. LANCASTER, OF NEWTON, MASSACHUSETTS, ASSIGNOR TO UNITED SHOE MACHINERY CORPORATION, OF PATERSON, NEW JERSEY, A CORPORATION OF NEW JERSEY.

PULLING-OVER MECHANISM.

Application filed December 23, 1925. Serial No. 77,277.

This invention relates to mechanism for use in the manufacture of boots and shoes for pulling uppers over lasts. Among its objects the invention aims to provide simple, compact and conveniently arranged means for operating upon an upper in different spaced locations about a shoe in preparation for the driving of the fastenings for holding the upper in pulled-over position, and is herein shown as embodied in a plurality of gripper and wiper units which present various novel features of construction and arrangement for the purposes in view, as hereinafter more particularly set forth.

A more particular object of the invention is to provide an organization of such a character that the upper-pulling means and the upper-fastening means will have ample space in which to perform their respective operations without the necessity of resorting to special design or to special movements of one or both of said means in order to avoid conflict between them. For the purposes in view, the construction herein shown comprises grippers which are so arranged as to extend outwardly from the lateral periphery of the shoe, instead of extending in directions substantially perpendicular to the plane of the shoe bottom as common heretofore.

Space is thus afforded opposite to the bottom of the shoe for the upper-fastening mechanism to be permanently positioned at a considerable distance from the field of operation of the grippers. The outwardly extending grippers, moreover, are arranged to be operated and controlled in such manner as to facilitate the introduction of the margin of the upper between the gripper jaws and to provide for the proper pulling of the upper over the last. As herein illustrated, each gripper is arranged to grip the margin of the upper in a plane substantially parallel to the plane of the shoe bottom and is independently mounted for upper-pulling movement about an axis which is located at a considerable distance outwardly from the shoe beyond the gripper jaws so that the effective pulling movement of the jaws is in a direction substantially perpendicular to the plane of the shoe bottom. To permit the margin of the upper to be readily inserted between the gripper jaws, the latter are arranged to present initially an upper-receiving opening which is opposite to the lateral periphery of the

shoe, and as herein shown the gripping of the upper is effected by closing movement of that jaw only which grips the upper on the outer face of the latter, so that in closing the tendency is to tighten the upper over the last in preparation for the subsequent pulling thereof after the margin of the upper has been gripped. As herein illustrated also, the opening of the gripper after the upper has been pulled is effected by movement of that jaw only which grips the upper on its inner face, this feature being of particular advantage in view of the character of the means herein-after described for wiping the upper inwardly over the bottom of the last. To accomplish effectively the objects in view, the different gripper jaws in the construction shown are arranged to be controlled independently of each other in respect to their closing and opening movements.

In accordance with a further feature of the invention there is provided a novel combination of means for gripping and pulling the upper and for wiping its margin inwardly over the bottom of the shoe. As herein shown, each gripper, arranged as hereinbefore described to grip the upper in a plane substantially parallel to the plane of the shoe bottom, is provided with means extending in substantially parallel relation to the plane in which the upper is gripped for wiping the margin inwardly after the upper-pulling operation. More particularly, the construction shown comprises a wiper pivotally mounted on that jaw of the gripper which grips the upper on its outer face, this wiper being operative to wipe the upper inwardly in response to longitudinal movement of the gripper. The position of the wiper is thus determined by that gripper jaw on which the wiper is mounted, by reason of which it is desirable that the release of the upper be effected by movement of the other jaw in the manner above explained.

The invention further provides a novel construction and arrangement of means for pulling the upper and for wiping it over the lateral periphery of the last toward the edge of the shoe bottom, i. e., for "upwiping" the upper. In its embodiment of this feature the construction shown comprises a wiper combined with each gripper to move therewith as a unit in the upper-pulling operation, this wiper being movable lengthwise of the grip-

per toward and from the shoe and arranged to serve after the upwiping operation to clamp the upper adjacent to the edge of the shoe bottom during the overwiping and upper-fastening operations.

The above and other features of the invention, including various novel details of construction and combinations of parts, will now be more particularly described by reference to the accompanying drawings and pointed out in the claims.

In the drawings,

Fig. 1 is a plan view, with parts in section, showing a gripper and wiper unit constructed in accordance with the present invention and illustrating the relation of the unit to shoe-positioning and upper-fastening mechanisms in a machine in which the shoe is positioned with its toe pointing vertically upward;

Figs. 2, 3 and 4 are views similar to Fig. 1, illustrating different successive positions of the parts in operating upon a shoe; and

Fig. 5 shows in rear elevation a group of units of the character illustrated in Fig. 1, positioned in different locations about a shoe.

For positioning the last with its shoe materials including the upper and the sole or insole (herein referred to generically as the sole regardless of the type of shoe), any suitable means may be utilized, the construction shown comprising a sole rest 10 such as is shown and described in detail in my copending application, Ser. No. 77,276 filed on December 23, 1925. As herein illustrated, the arrangement is such that the shoe is positioned with its toe pointing vertically upward so as to present the top of the forepart conveniently within view of the operator of the machine, although the invention is not limited to an organization in which the shoe is positioned in this particular manner. For pulling the upper and for wiping it into a position to be fastened to the sole, it is contemplated that there will be utilized a plurality of gripper and wiper units constructed and arranged for purposes of this invention as hereinafter more particularly set forth. While the invention is not limited to any particular number or arrangement of such units, there may be utilized, as shown in Fig. 5, a single unit at the end of the toe and other units at the opposite sides of the forepart of the shoe, these different units being substantially identical in construction except as to width.

The construction of one of the gripper and wiper units is shown in detail in Fig. 1. For gripping and pulling the upper there are provided co-operating gripper jaws 12 and 14 arranged to engage the upper respectively upon the outer and inner surfaces of the latter. Both the gripper jaws are pivotally mounted at 16 on a gripper bar 18 which is movable lengthwise in directions toward and from the

shoe and is pivotally connected at 20 to a slide 22 whereby such movements are imparted thereto, this slide being mounted in a fixed bracket 24. The slide 22 at its outer end is connected to a bell crank 26 to which movement is imparted by a link 28 connected in turn to suitable operating mechanism not herein illustrated. The pivotal connection between the gripper bar 18 and the slide 22 permits the gripper to swing in directions heightwise of the shoe, and for imparting such movements to the gripper there is provided a yoke 30 which is pivotally connected to the gripper bar 18 at the opposite sides of the latter and is operated by a member 32 to which the yoke is pivotally connected at 34 so as to permit longitudinal movements of the gripper in response to the action of the slide 22.

The gripper jaws 12 and 14 are movable independently of each other about the pivot 16 and are independently controlled with respect to such movements by separate operating connections. For this purpose there is slidably mounted in the gripper bar 18 a rod 36 which is connected by a link 38 to the gripper jaw 12, so that swinging movements of this jaw toward and from the other jaw are effected by movements of the rod 36. For controlling the jaw 14 there is provided a rod 40 which extends along one side of the bar 18 through the yoke 30. It will be understood that the rods 36 and 40, and likewise the other connections herein described for imparting the various movements to the different operating instrumentalities, are to be connected to suitable mechanical means for operating them in the required time relation to one another, such operating means not being illustrated, since the details thereof are merely matters of design and form no part of the present invention.

In accordance with one of the objects of the present invention, the gripper is utilized after the pulling of the upper to wipe the margin of the upper inwardly over the sole. To this end, there is pivotally mounted on the gripper jaw 12 a wiper 42 which has its inner end slightly upturned to assist in guiding it over the shoe bottom, this wiper being free to rock to a limited extent on the gripper jaw about an axis extending laterally of the jaw to permit it to apply a substantially uniform wiping pressure across the margin of the upper. It will be understood that the gripper receives its longitudinal wiping movement from the slide 22 when the latter is operated by the bell crank 26.

Combined with the gripper there is further provided a device for engaging the upper upon the lateral periphery of the last and for wiping the upper heightwise of the last to the edge of the last bottom. This device comprises a slide or wiper 44 which is mounted adjacent to the gripper bar 18

and is guided by a lateral extension 46 on the bar, the wiper having at its inner end a facing or pad 48 of yieldable material for engagement with the shoe. It will thus be seen that the wiper 46 and the gripper are moved as a unit heightwise of the shoe by the action of the member 32. Movement of the wiper 44 lengthwise of the bar 18 to carry it into and out of engagement with the shoe is effected by means of a link 50 connected to suitable operating mechanism.

For fastening the upper after it has been wiped inwardly over the sole, there may be conveniently utilized tacking mechanism of the same character as that shown and described in my copending application hereinbefore mentioned, although the invention is not dependent upon the use of fastening means of any particular character. Fastening mechanism such as shown in said copending application comprises a plurality of tack holders or tubes with tack drivers therein, the tubes and the drivers being positioned opposite to the bottom of the shoe and moved lengthwise toward the shoe and then operated to drive the tacks after the overwiping operation. For illustrative purposes a single tack tube 52 and its tack driver 54 are shown in the drawings. The number of such 30 tacking devices will depend on the number of points at which it is desired to fasten the upper, the drawings illustrating an arrangement whereby three tacks are driven at each side of the forepart of the shoe and a single tack at the end of the toe. The arrangement is such that the tacks are driven through that gripper jaw which is next to the bottom of the shoe and through the wiper mounted thereon, the jaw and the 40 wiper being provided with slots, indicated by dotted lines at 56 in Fig. 5, to permit the tacks to be driven. For supporting the shoe against the pressure of the overwiping and fastening means there is provided a shoe 45 rest 58.

In the operation of a machine provided with upper-pulling and wiping means such as above described the shoe is presented in the position illustrated in Fig. 1, the gripper jaws 12 and 14 being arranged to present at that time a comparatively wide opening opposite to the lateral periphery of the shoe to permit the upper to be readily inserted between them. It will be observed that, as the 50 jaws are thus positioned, the upper-engaging face of the jaw 14 extends in a general direction substantially parallel to the shoe bottom. The gripping of the upper is preferably effected by swinging movement of the jaw 12 only, in response to the action of the rod 36, while the opposite jaw 14 is held stationary by its rod 40. In this manner the jaw 12 tends to tighten the upper over the last as it swings heightwise of the shoe into 55 position to grip the margin of the upper

against the jaw 14. After the margin of the upper has thus been gripped in a plane substantially parallel to the plane of the shoe bottom, the pulling of the upper is effected by swinging movement of the gripper about 70 its pivot 20 in response to the action of the member 32. It will be observed that the pivot 20 about which the gripper swings is located at a considerable distance farther outwardly from the shoe than the gripper jaws and substantially in the plane of the shoe bottom, so that the effective pulling movement of the jaws is in a direction substantially perpendicular to the plane of the shoe bottom.

After the margin of the upper has been gripped by the gripper jaws, and it may be after the jaws have begun their pulling movement, the wiper 44 is moved inwardly into engagement with the upper on the lateral periphery of the shoe by the action of the member 50, so that in the continued upper-pulling movement of the gripper the wiper acts to wipe the upper heightwise of the shoe toward the edge of the shoe bottom. Fig. 2 illustrates the conditions at an intermediate stage in 80 the upper-pulling and upwiping operations, while in Fig. 3 the parts are shown in the positions which they occupy after the wiper 44 has arrived at the limit of its upwiping movement. The opening of the gripper to 85 release the upper is preferably effected when the gripper and wiper unit has arrived substantially or nearly at the end of its operative movement heightwise of the shoe. When the gripper and wiper unit has thus arrived at the end of its movement, the gripper jaw 12 and the wiper 42 are in position to begin the overwiping operation. Release of the upper by the gripper is effected by swinging 90 movement of the jaw 14 only, this jaw being swung outwardly far enough to be clear of the tacking mechanism when the latter is operated to drive the tacks.

After the gripper has released the upper, 105 the overwiping operation is effected by longitudinal movement of the gripper in response to the action of the slide 22, the gripper jaw 12 being held at this time by its operating connections in position to bring effective wiping pressure to bear upon the upper through the wiper 42. During this overwiping operation the wiper 44 remains in position to act as a clamp to assist in holding the upper on the lateral periphery of the last. At the end of the overwiping operation the tacking mechanism is moved toward the bottom of the shoe and the tacks are driven. Thereafter the various parts of the machine are returned to their starting positions and the shoe is released.

It will be observed that since the gripper and wiper units are arranged to radiate outwardly from the shoe in directions transverse to the lateral periphery of the shoe and, as herein shown, in directions substantially par-

allel to the plane of the shoe bottom, there is afforded ample space opposite to the bottom of the shoe for the upper-fastening mechanism to be permanently positioned and operated at a considerable distance from the field of operation of the grippers, so that the organization does not present any special problems resulting from danger of possible conflict between the grippers and the upper-fastening devices.

While the invention is herein illustrated by reference to an organization comprising gripper and wiper units substantially identical in construction for operating upon the upper at the end and at the opposite sides of the shoe, the invention is not thus limited, and references in the claims to a plurality of grippers or of gripper and wiper units are not intended as definitions of an organization in which all of the grippers or of the gripper and wiper units that are utilized are necessarily constructed as set forth.

Having described the invention, what I claim as new and desire to secure by Letters Patent of the United States is:—

1. In mechanism of the class described, the combination with shoe-positioning means, of a plurality of grippers for pulling the upper respectively in different spaced locations about the shoe, said grippers being arranged to radiate outwardly from the shoe in directions substantially parallel to the plane of the shoe bottom and each being pivotally mounted independently for swinging movement heightwise of the shoe to pull the upper.

2. In mechanism of the class described, the combination with shoe-positioning means, of a plurality of grippers for pulling the upper respectively in different spaced locations about the shoe, said grippers extending outwardly in directions transverse to the lateral periphery of the shoe and each being independently mounted for upper pulling movement heightwise of the shoe about an axis located farther outwardly from the lateral periphery of the shoe than its upper-engaging portion.

3. In mechanism of the class described, the combination with shoe-positioning means, of a plurality of grippers for pulling the upper respectively in different spaced locations about the shoe, each of said grippers being pivotally mounted independently for upper pulling movement heightwise of the shoe about an axis located substantially in the plane of the shoe bottom and farther outwardly from the shoe than its upper-engaging portion.

4. In mechanism of the class described, the combination with shoe-positioning means, of a plurality of grippers for pulling the upper respectively in different spaced locations about the shoe, said grippers being arranged to radiate outwardly from the portions of the lateral periphery of the shoe where they

engage the upper and each comprising a pair of jaws for gripping the upper in a plane substantially parallel to the plane of the shoe bottom throughout the upper-pulling operation.

5. In mechanism of the class described, the combination with shoe-positioning means, of a plurality of grippers for pulling the upper respectively in different spaced locations about the shoe, said grippers being arranged to radiate outwardly from the lateral periphery of the shoe and each comprising a pair of jaws for gripping the upper in a plane substantially parallel to the plane of the shoe bottom, each pair of jaws being independently mounted for upper-pulling movement heightwise of the shoe about an axis located farther outwardly from the shoe than said jaws.

6. In mechanism of the class described, the combination with shoe-positioning means, of a plurality of grippers for pulling the upper respectively in different spaced locations about the shoe, each of said grippers comprising a pair of jaws each mounted to swing toward and from the other and separately controlled in respect to such swinging movements.

7. In mechanism of the class described, the combination with shoe-positioning means, of a plurality of grippers for pulling the upper respectively in different spaced locations about the shoe, each of said grippers comprising a pair of jaws separately controlled in respect to opening and closing movements and arranged to grip the upper in a plane substantially parallel to the plane of the shoe bottom.

8. In mechanism of the class described, the combination with shoe-positioning means, of a plurality of grippers for pulling the upper respectively in different spaced locations about the shoe, said grippers being arranged to radiate outwardly from the lateral periphery of the shoe and each comprising a pair of separately controlled jaws each mounted to swing toward and from the other and both mounted to swing as a unit heightwise of the shoe to pull the upper.

9. In mechanism of the class described, the combination with shoe-positioning means, of a plurality of grippers for pulling the upper respectively in different spaced locations about the shoe, each of said grippers comprising a pair of jaws arranged to grip the upper in a plane substantially parallel to the plane of the shoe bottom, and means for effecting the gripping of the upper by movement of that jaw only which engages the outer face of the upper.

10. In mechanism of the class described, the combination with shoe-positioning means, of a plurality of grippers for pulling the upper respectively in different spaced locations about the shoe, each of said grippers compris-

ing a pair of jaws arranged to present an upper-receiving opening opposite to the lateral periphery of the shoe, and means for effecting the gripping of the upper by closing 5 movement heightwise of the shoe of that jaw only which engages the outer face of the upper.

11. In mechanism of the class described, the combination with shoe-positioning means, 10 of a plurality of grippers for pulling the upper respectively in different spaced locations about the shoe, each of said grippers comprising a pair of jaws arranged to grip the upper in a plane substantially parallel to the 15 plane of the shoe bottom, and means for presenting that jaw which engages the inner face of the upper in an upper-receiving position in which its upper-engaging face is substantially parallel to the plane of the shoe bottom and 20 for effecting the gripping of the upper by movement of the other jaw.

12. In mechanism of the class described, the combination with shoe-positioning means, 25 of a plurality of grippers for pulling the upper respectively in different spaced locations about the shoe, each of said grippers comprising a pair of jaws arranged to be independently controlled in respect to opening and closing movements, and means for effecting 30 the gripping of the upper by movement of one of said jaws and for effecting the release of the upper by movement of the other jaw.

13. In mechanism of the class described, the combination with shoe-positioning means, 35 of a plurality of grippers for pulling the upper respectively in different spaced locations about the shoe, each of said grippers comprising a pair of jaws arranged to grip the upper in a plane substantially parallel to the plane 40 of the shoe bottom, and means for effecting the gripping of the upper by movement of that jaw only that engages the outer face of the upper and for effecting the release of the upper by movement of the other jaw only.

45 14. In mechanism of the class described, the combination with shoe-positioning means, of a plurality of grippers for pulling the upper respectively in different spaced locations about the shoe, each of said grippers comprising a pair of jaws arranged to grip the upper in a plane substantially parallel to the plane 50 of the shoe bottom and having thereon means for wiping the upper inwardly over the bottom of the shoe in locations only where the 55 pulling of the upper takes place.

15. In mechanism of the class described, the combination with shoe-positioning means, of a plurality of grippers for pulling the upper respectively in different spaced locations 60 about the shoe, each of said grippers having pivotally mounted on one of its jaws a wiper for wiping the upper inwardly over the bottom of the shoe.

65 16. In mechanism of the class described, the combination with shoe-positioning means,

of a plurality of grippers for pulling the upper respectively in different spaced locations about the shoe, each of said grippers comprising a pair of jaws arranged to grip the upper in a plane substantially parallel to the plane 70 of the shoe bottom, and a wiper mounted on one of the jaws of each gripper on the opposite side from its upper-gripping face and of substantially the same extent lengthwise of the edge of the upper as said gripping face 75 for wiping the upper inwardly over the bottom of the shoe.

17. In mechanism of the class described, the combination with shoe-positioning means, of a plurality of grippers for pulling the upper 80 respectively in different spaced locations about the shoe, each of said grippers having wiping means thereon and being mounted for swinging movement to pull the upper and for rectilinear movement to wipe the upper inwardly over the bottom of the shoe. 85

18. In mechanism of the class described, the combination with shoe-positioning means, of a plurality of grippers arranged to radiate outwardly from the lateral periphery of the 90 shoe for pulling the upper respectively in different spaced locations about the shoe and each comprising a pair of jaws for gripping the upper in a plane substantially parallel to the plane of the shoe bottom, each of said grippers having wiping means thereon and being mounted for swinging movement heightwise of the shoe to pull the upper and for longitudinal movement to wipe the upper inwardly over the bottom of the shoe. 95

19. In mechanism of the class described, the combination with shoe-positioning means, of a plurality of grippers arranged to radiate outwardly from the lateral periphery of the shoe for pulling the upper respectively in different spaced locations about the shoe and each comprising a pair of upper-gripping jaws, one of the jaws of each of said grippers having thereon wiping means for wiping the upper inwardly over the bottom of the shoe 100 in response to inward movement of said jaw over the shoe and provided with an opening through which a fastening may be driven for holding the upper. 105

20. In mechanism of the class described, the combination with shoe-positioning means, of a plurality of gripper and wiper units for operating respectively in different spaced locations about the shoe, each of said units being movable heightwise of the shoe to pull the 110 upper and including a wiper arranged to engage the upper on the lateral periphery of the shoe and to wipe it toward the edge of the shoe bottom in the operative movement of said unit. 120

21. In mechanism of the class described, the combination with shoe-positioning means, of a plurality of gripper and wiper units for operating respectively in different spaced locations about the shoe, said units being ar- 125

ranged to radiate outwardly from the shoe in directions substantially parallel to the plane of the shoe bottom and each comprising a gripper for pulling the upper and a wiper for wiping the upper heightwise of the shoe toward the edge of the shoe bottom.

22. In mechanism of the class described, the combination with shoe-positioning means, of a plurality of gripper and wiper units for operating respectively in different spaced locations about the shoe, each of said units comprising a gripper arranged to extend outwardly from the lateral periphery of the shoe and a wiper movable longitudinally of said gripper into engagement with the upper adjacent to the gripper for wiping the upper heightwise of the shoe.

23. In mechanism of the class described, the combination with shoe-positioning means, of a plurality of gripper and wiper units for operating respectively in different spaced locations about the shoe, each of said units comprising a gripper arranged to grip the upper in a plane substantially parallel to the plane of the shoe bottom and movable heightwise of the shoe to pull the upper and a wiper movable with said gripper to upwipe the upper.

24. In mechanism of the class described, the combination with shoe-positioning means, of a plurality of gripper and wiper units for operating respectively in different spaced lo-

cations about the shoe, each of said units comprising a gripper for pulling the upper and a wiper movably mounted on said gripper for engaging the upper on the lateral periphery 35 of the shoe to upwipe the upper.

25. In mechanism of the class described, the combination with shoe-positioning means, of a plurality of gripper and wiper units for operating respectively in different spaced locations about the shoe, each of said units comprising an upper-pulling gripper having means thereon for wiping the upper inwardly over the bottom of the shoe and also comprising a wiper for wiping the upper over the lateral periphery of the shoe.

26. In mechanism of the class described, the combination with shoe-positioning means, of a plurality of gripper and wiper units for operating respectively in different spaced locations about the shoe, each of said units comprising a gripper movable heightwise of the shoe to pull the upper and having thereon means for subsequently wiping the upper inwardly over the bottom of the shoe and comprising also a wiper arranged to engage the upper on the lateral periphery of the shoe and movable with the gripper to upwipe the upper in the upper-pulling operation.

In testimony whereof I have signed my 60 name to this specification.

JOHN T. LANCASTER.
